UNITED STATES PATENT OFFICE.

AUGUST LEIB, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY.

VARIABLE CAPACITOR.

Application filed September 14, 1923, Serial No. 662,612, and in Germany August 17, 1922.

My invention relates to variable condensers used to vary the capacitance of an electric circuit and has for its object to provide a variable condenser which will be 5 cheap to manufacture and yet rugged and accurate in use.

The present application covers an improvement upon the mechanical and electrical construction of continuously variable 10 condensers with a solid dielectric, especially adapted to receiving purposes. The demands and requirements that must be satisfied in the formation and construction of continuously variable condensers with solid dielectrics, such as small losses, continual 15 variability by the aid of as simple a mechanism as feasible, low weight and cheapness, have been taken into consideration to a large extent in the development of the condenser of this invention, which also affords the prerequisites for cheap, large scale manufacture, since the condenser does not require high-precision workmanship.

The demand that the losses shall be low 20 and the complete fulfilment of the same makes the use of a high-grade dielectric of paramount importance. For this reason the material most suitable for the purpose is mica, since, as is well known, this material 25 involves only very small losses even when of extremely thin lamination. The economical use of this high-grade dielectric of a thickness varying between 0.02 and 0.03 mm., on the one hand, is made possible by 30 perfect and homogeneous contact between the solid coats and the mica, so that inclusions of air spaces involving a lower dielectric constant are avoided, while, on the other hand, by the constructional formation of the 35 adjusting mechanism, the thin-walled dielectric is made entirely free from mechanical stresses in spite of the absolute contact.

Fig. 1 shows a cross section of my condenser.

Figs. 2, 3 and 4 show one form of my condenser in different rotative positions.

Figs. 5, 6 and 7 show another form of my condenser in different rotative positions.

Fig. 8 is a cross section of my condenser 50 mounted in a dial which is mounted in a support or panel.

Fig. 9 is a front view of the arrangement shown in Fig. 8.

Referring to Figs. 1 to 4 inclusive, C de- 55 notes the extremely thin mica laminae, each

having the thickness of 0.1 mm., which together with annular ring D form a closed shell or casing. This shell is half filled with the liquid condenser plate or coat A which may be any liquid conductive substance such as, for instance, mercury. To eliminate sensitiveness to shocks and vibrations the other half of shell is filled with a paraffin oil F. B₁ and B₂ denote the solid condenser plates, each substantially semi-circular in shape, which are fastened to the exterior of the shell. They are connected together to form in effect a single condenser plate. A lead wire G passing through an opening in ring D forms electrical connection with the liquid condenser plate A. 60

It can easily be seen that as the dielectric shell is rotated, the liquid coat A will always remain in the bottom with the paraffin oil F floating on top. When the liquid coat A is entirely out of register with the solid plates B₁ and B₂, as shown in Fig. 2, there is minimum capacitance between the opposite condenser plates. When the dielectric shell is rotated 90° to the position shown in Fig. 3, the capacitance between the liquid condenser plate A and solid condenser plates B₁ and B₂ is substantially one-half the maximum capacitance of the condenser. When the dielectric shell is rotated a further 90°, as shown in Fig. 4, so that the solid plates and the liquid plate are in register, the capacitance of the condenser is maximum. 70

Referring now to Figs. 5, 6 and 7, there is illustrated a condenser identical with the condenser shown in Figs. 1 to 4 inclusive with the exception that each set of solid plates B₁ and B₂ are divided in half to form separate sets of condenser plates. The plates B₁ and B₂ of each set are connected together to form, in effect, a single plate. This type of condenser may be called a double condenser since there are two separate capacitances, one between the liquid plate A and one set of solid plates and the other between liquid plate A and the other set of solid plates. Fig. 6 shows substantially no capacitance between either set of solid condenser plates and the liquid condenser plate. Fig. 5 shows a condition of maximum capacitance between the liquid plate and one set of solid condenser plates with substantially no capacitance between the liquid condenser plate and the other set of solid condenser plates, while Fig. 7 shows these con- 80 85 90 95 100 105 110

ditions reversed by rotating the dielectric shell 180°.

Referring to Figs. 8 and 9, the condenser is shown mounted in a pocket 3 in the rear face of the dial E which is made of insulating material. The dial E is positioned in an opening in support or panel P and is rotatably held there by means of plates 1 and 2 appropriately fixed to the panel. The dial 10 E is provided with an annular groove 4 which provides a journal portion to cooperate with the plate 2 which operates as a bearing. The plate 4 and the dial E adjacent plate 4 are provided with markings 15 to tell the operator the position of the condenser.

The plate 1 is provided with an opening 5 thru which the wires B and G leading to the solid and liquid plates respectively pass.

20 It should be noted that by appropriately shaping the solid plates or the chamber for holding the liquid plate, the effective areas of the plates, and hence the capacitance may be made to vary, according to any desired 25 law when the dielectric is rotated by equal increments.

By the principle described it is made 30 feasible to build not only large but also very small continuously variable condensers with the use of extremely thin-walled mica laminae. No mechanical stressing of the mica 35 laminations happens, while short-circuiting

between the coats of opposite polarity is entirely precluded if the construction is chosen of an appropriate nature.

Having described my invention, what I claim is:

1. A variable condenser comprising a rotatable dielectric, a condenser plate fixed on one side of said dielectric, a stationary liquid condenser plate on the other side of said dielectric, and fluid means for preventing undesired motion of the liquid condenser plate, due to its sensitiveness to shock and vibration. 45

2. A variable condenser comprising a rotatable shell of dielectric material, a condenser plate fixed on the exterior of said shell, a stationary liquid condenser plate within said shell, and a body of insulating material whose specific gravity is less than that of said liquid condenser plate also within said shell for preventing undesired motion of the liquid condenser plate. 50

3. In combination, a panel having an opening therein and an annular bearing member fixed to said panel, a rotatable dial within said opening having an annular journal portion cooperating with said bearing member and also having a knob and an indicating portion extending from said knob to said journal portion, said dial containing means for varying a constant of an electric circuit. 55

AUGUST LEIB.
